INFANT'S BIB

Ila E. Faughnder, 2836 Francis Ave.,
Los Angeles, Calif. 90005

Substituted for abandoned design application Ser. No.
80,570, June 10, 1964. This application Aug. 19, 1965,
Ser. No. 86,640

Term of patent 14 years

(Cl. D3—26)

FIG. 1.

FIG. 2.

FIG. 3.

FIG. 4.

FIG. 5.

FIGURE 1 is a front elevational view of an infant's bib embodying my new design;

FIGURE 2 is a rear elevational view thereof;

FIGURE 3 is a right side elevational view thereof;

FIGURE 4 is a top plan view thereof; and

FIGURE 5 is a bottom plan view thereof.

The characteristic features of my design reside in the combination on an infant's bib of the type disclosed of a narrow band which extends horizontally across the front and the small supplemental bib portion which extends across the neck to the back and is of similar size and shape on both the front and the reverse sides of the bib, all as shown on the drawing.

This is a substitute application for application Serial No. D-80,570, now abandoned.

I claim:

The ornamental design for an infant's bib, substantially as shown and described.
